UNITED STATES PATENT OFFICE.

CLEMENTS B. KOSTERS, OF BUFFALO, NEW YORK.

SHOE-HOLDER.

SPECIFICATION forming part of Letters Patent No. 755,015, dated March 22, 1904.

Application filed May 26, 1903. Serial No. 158,836. (No model.)

To all whom it may concern:

Be it known that I, CLEMENTS B. KOSTERS, a citizen of the United States, residing at Buffalo, in the county of Erie and State of New York, have invented certain new and useful Improvements in Shoe-Holders, of which the following is a specification.

This invention relates to an improved shoe-holder, which is adapted to be attached to a wall or the like and which consists of a plurality of members having parts adapted to fit within a shoe or the like, and one of said members having a curved slide portion, and another of said members being adapted to slide on said curved portion, the curving of the slide portion giving a partial turning or pivotal movement to the slide member as it moves on the slide portion, whereby it has a curved path of movement.

20 The invention also has reference to a spring means for holding the upper in stretched position.

The main object of the invention is to arrange one of the members so that it will have both a sliding movement and a pivotal movement on another of said members, or both swing and slide in a curved path, so that the depending shoe-supporting portion of the first-mentioned member will have a greater range of movement than that portion of said member adjacent to the slide portion of the last-mentioned member, which enables the use of a comparatively short slide portion, while providing sufficient range of adjustment to support different lengths of shoes, reduces the weight, and stiffens and strengthens the construction.

Another object is to hold the upper in a stretched unwrinkled condition, so that it can be readily and easily cleaned or polished.

The invention also relates to certain details of construction, all of which will be fully and clearly hereinafter described and claimed, reference being had to the accompanying drawings, in which—

Figure 1 is a side elevation of the improved shoe-holder with the outline of a shoe shown in dotted lines in position thereon. Fig. 2 is a plan view of the improved shoe-holder. Fig. 3 is a detached front view of the supporting-

bracket or hinge-plate. Fig. 4 is a detached side view of the supporting-bracket or hinge-plate. Fig. 5 is a section on line *a a*, Fig. 4. Fig. 6 is a side elevation of the improved shoe-holder, a section being taken through the movable member and the supporting-bracket or hinge-plate, the movable member being shown in one position in full lines and in another position in dotted lines. Fig. 7 is a front elevation of the improved shoe-holder. Fig. 8 is a detached front elevation of the movable member. Fig. 9 is a detached rear elevation of the movable member. Fig. 10 is a detached bottom view of the toe-piece. Fig. 11 is a section on line *b b*, Fig. 1, to show the method of fastening the toe-piece to the stationary member.

In referring to the drawings for the details of construction like numerals designate like parts.

70 In the construction shown in the drawings the stationary member 1 comprises an outwardly-extending curved portion 2 and a depending portion 3, which has a short horizontally-extending lug 4, upon which a toe-piece 5 is fastened. (See Figs. 1 and 6.) The bottom surface of the curved portion 2 is serrated or toothed, as at 6, and a movable member 7, having a vertical slot or opening 8, through which the curved portion 2 passes, 75 is adapted to slide on the curved portion 2 of the stationary member 1.

The slot or opening 8 in the movable member 7 is formed as shown in Figs. 6, 8, and 9, the bottom wall 9 being formed so as to leave 85 a sharp edge 10, which engages with the teeth or serrations 6 on the bottom surface of the curved portion 2. The top wall of the opening 8 is curved, as shown at 11, so that the movable member 7 will easily slide upon the top surface of the curved portion 2.

90 The upper end of the movable member 7 is in the form of a knob or handle 12, by means of which the movable member 7 may be easily moved back and forth upon the curved portion 2 of the stationary member. The lower extremity of the movable member 7 enlarges at 13 and forms a heel portion which fits in and supports the heel of the shoe. (See Fig. 1.)

95 The top and bottom surfaces of the curved 100

portion 2 are of different curvatures, and by referring to Fig. 6 it will be seen that as the movable member 7 is moved backward from the toe-piece 5 it will travel in a curved path and gradually turn pivotally and assume a more perpendicular position.

The toe-piece 5, formed as shown in Figs. 1, 2, 6, 7, 10, and 11, is provided with two downwardly-extending ribs 14, between which 10 the lug 4 is adapted to fit, the toe-piece 5 being adjustably fastened to the lug 4 by a bolt 15, which screws through one of the ribs 14 and has its end seated in a shallow depression 16, formed in the side of the lug 4. The toe-piece 5 is preferably formed hollow, as shown, to lighten the construction.

Means are provided for holding the shoe-upper in stretched unwrinkled position, which preferably consists of a standard or bar extending from one member and supporting a spring or springs which are adapted to be detachably connected to the shoe-upper. This means is preferably formed as follows: An upwardly-extending standard or bar 17, having a forked lower end 18, is secured to the stationary member 1 so as to be easily removed therefrom, the ends of the fork 18 being provided with inwardly-extending flanges 19, which fit in depressions 20, formed in 25 each side of the stationary member 1. (See Figs. 1, 2, and 7.) The depressions 20 are comparatively long and narrow and taper from their outer to their inner ends, the purpose of which is to tightly wedge the flanges 19 in 30 the depressions 20. The upper end of the standard or bar 17 is slotted, as at 21, and two spiral springs 22 are supported in the slotted upper end 21 thereof. The springs 22 are preferably formed of one piece of wire having a straight central connecting portion 23, which fits in the slot 21. (See Figs. 1 and 7.) The lower ends of the springs 22 are bent 35 to form hooks 24, which may be hooked into the eyes of the shoe, thereby stretching the shoe-upper and practically removing all wrinkles, so as to permit the entire shoe to be 40 easily polished and cleaned.

The shoe-holder is supported from a bracket 25, fastened to a wall or the like by two hinge-pins 26, which extend vertically upward and downward from the inner end of the stationary member 1 and fit in openings 27, formed in lugs 28, extending from the bracket 25. The lower lug 28 has an outwardly-extending 50 portion 29, provided with a tapering V-shaped depression 30 in its outer end, and a tapering lug 31, projecting downwardly from the bottom surface of the stationary member 1, has its inner surface beveled to fit in the V-shaped 55 depression 30 in the portion 29 and securely holds the shoe-holder in operating position while a shoe is being cleaned or polished. By 60 lifting the stationary member sufficiently to disengage the lug 31 from the depression 30

the shoe-holder may be turned toward the 65 wall when not in use. The bracket 25 and lug 28 are cut away at 32, 33, and 34, respectively, so as to permit the stationary member to be removed without removing the bracket from the wall.

The great advantage of this form of shoe-holder is that the slideable member slides on the stationary member in a curved path, so that it swings its lower depending shoe-supporting portion and causes it to have a greater 75 range of movement than the upper portion.

I claim as my invention—

1. An improved shoe-holder comprising a plurality of members adapted to fit within and support a shoe and one of said members 80 having a curved portion and another being slidably mounted on said curved portion, substantially as set forth.

2. An improved shoe-holder comprising a plurality of members having depending parts 85 adapted to extend within and support a shoe and one of said members having a curved portion and another being adapted to have a combined sliding and pivotal movement on said curved portion, substantially as set forth. 90

3. An improved shoe-holder comprising a stationary member, a slideable member having support from the stationary member, said stationary member having means whereby the slideable member is adapted to have a curved 95 path of movement and said members having depending parts adapted to fit within the toe and heel of a shoe, substantially as set forth.

4. An improved shoe-holder comprising a stationary member having a curved portion, 100 a slideable member having a slot through which the curved portion extends and adapted to have a combined longitudinal sliding pivotal movement on said curved portion; said members having depending parts adapted to fit 105 within the toe and heel of a shoe, substantially as set forth.

5. In a device of the class described, a plurality of adjustable members having means for supporting the lower portion of a shoe or 110 the like, one of said members having tapering depressions, a standard having a forked end provided with inwardly-extending flanges adapted to wedge in the depressions and a spring supported from the standard and adapted to support the upper in stretched position. 115

6. In a device of the class described, a plurality of adjustable members having means for supporting the lower portion of a shoe or the like, one of said members having a depression, a standard having a forked lower end detachably engaging in said depression, and a spring depending from said standard and adapted to be attached to a shoe-upper. 120
